George W. Dugwell
ATTORNEY

UNITED STATES PATENT OFFICE.

GEORGE E. BISHOP, OF CLEVELAND, OHIO.

AUTOMOBILE INCLOSURE.

Application filed January 9, 1922. Serial No. 527,963.

To all whom it may concern:

Be it known that I, GEORGE E. BISHOP, a citizen of the United States, resident of Cleveland, county of Cuyahoga, and State of Ohio, have invented new and useful Improvements in Automobile Inclosures (Case Q), of which the following is a specification, the principle of the invention being herein explained and the best mode in which I have 10 contemplated applying that principle, so as to distinguish it from other inventions.

My invention relates to vehicle side inclosures and particularly to an automobile inclosure adapted to be supported upon an 15 automobile door so as to ride in and out with the latter as the same is opened and shut. The particular improvements of this application relates to means for holding the upper inclosure edge in its desired relation to the 20 door.

The annexed drawings and the following description set forth in detail certain means embodying my invention, such disclosed means, however, constituting but a few of 25 the various embodiments in which the principles of my invention may be used.

In said annexed drawings:

Figure 1 represents a side elevation of a simple form of the collapsible type of my 30 invention, showing also a broken elevation of the automobile body including the doors thereof;

Figure 2 represents a transverse vertical section, taken in the plane indicated by the 35 line II-II, Figure 1;

Figure 3 represents an elevation, similar to Figure 1, of another and somewhat more expensive form of the collapsible type of 40 this invention, showing also modified means for stiffening the lower inclosure edge so as to insure a satisfactory lapping of the inclosure over the door and the body. Incidentally these lower stiffening means prevent the tearing of the fabric when the 45 inclosure is under tension.

Figure 4 represents a horizontal longitudinal section, taken in the plane indicated by the line IV-IV, Figure 3;

Figure 5 represents an enlarged fragmentary transverse vertical section, taken in the 50 plane indicated by the line V-V, Figure 3;

Figure 6 represents a fragmentary elevation of a second modified form of the collapsible type of my invention;

Figure 7 represents, upon an enlarged scale, an elevation, at right angles to the

elevation of Figure 6, of a portion of the supporting rod forming one of the elements of the form of inclosure shown in Figure 6;

Figure 8 represents a transverse vertical section, also upon an enlarged scale, taken in the plane indicated by the line VIII-VIII, Figure 6;

Figure 9 represents a side elevation of a rigid frame type of inclosure embodying my 65 invention;

Figure 10 represents, upon an enlarged scale, a fragmentary transverse horizontal section taken in the plane indicated by the line X-X, Figure 9;

Figure 11 represents a fragmentary side elevation of a modified form of rigid frame type of inclosure; and

Figure 12 represents an elevation, at right angles to the elevation of Figure 11, of a 75 supporting rod forming one of the elements of the type of inclosure shown in Figure 11.

Referring to the annexed drawings, in which the same elements are represented, respectively, by the same ordinals in the several views, I suggest the body of an automobile by the ordinal 1, the same having the front door 2, and rear door 3. Upon the door 2, for instance, I support one of my improved side inclosures comprising suitable 80 fabric 4 provided with front and rear transparencies 5 and 6, respectively, disposed in the door heading and back of the door heading, as plainly shown in Figures 1, 3 and 9. The inclosure is provided with strengthening 85 means, is supported upon the door 2 so as to ride in and out with the latter, and breaks, as it is opened and shut, in the line of the door hinges 2', all as will be hereinafter fully described.

Referring to the collapsible types of inclosures shown in Figures 1 to 8, the main elements for holding the curtain taut and rigid in longitudinal and transverse planes, respectively, consist of a metallic bar 7 and a rod 8, the latter serving also to support the inclosure upon the door 2. The bar 7 is secured to the fabric 4, preferably incorporated within the latter, adjacent the top edge of the inclosure, and extends from a point contiguous the opening edge 4² of the inclosure back to a point slightly short of the breaking point of the inclosure as the same is opened and shut with the door. The transverse or vertical member for holding 100 the curtain taut, which is also a stretching and supporting member, is secured to the 105

fabric 4, and preferably, as shown in the accompanying drawings, is secured to the longitudinal strengthening member 7, this connection being one that allows the removal 5 of member 8 from member 7 or the pivotal movement of member 8 relatively to member 7, when the inclosure is removed from the door 2, so that the curtain can be rolled or folded for convenient storage. The connection 10 of the strengthening member 7 and the supporting member 8 is at a point removed from the lapping edge 4², as shown in Figures 1, 3 and 6, so that the strengthening member 7, being thus connected to the support 8 intermediate of the ends of the member 7, can rock upon the support 8 in a vertical plane, for the purpose hereinafter fully described.

I provide the lower edge of the inclosure 20 with tensioning means for holding the upper inclosure edge in its proper horizontal relation to the door and, preferably, I provide these tensioning means adjacent the closing edge of the inclosure. These tensioning 25 means in the types of invention illustrated take the form of co-operating button elements provided upon the upper edge of the door and the lower edge of the inclosure. As shown in the accompanying drawings, I 30 have provided the door 2 with a button head 14 and the inclosure with a co-operating button socket 14'. This button fastener produces an effective stretch in the inclosure and holds the top of the curtain in its proper 35 relation to the door. If the inclosure tends to sag, the tensioning means will rock the same upon the connection between the member 7 and support 8 and throw the rear of the inclosure up into its proper position. In 40 order that a satisfactory lapping of the inclosure over the door and body may be obtained, I provide the fabric with lower stiffening means and preferably incorporate the latter with the fabric in the section where 45 the tensioning means are provided. In Figures 1 and 2, for instance, I show a thin sheet metal stiffening member 10 and in Figures 3 and 6 a section of wire netting 10'. These lower stiffening means incidentally strength- 50 en the fabric against tearing when the inclosure is tensioned.

The inclosure above described is designed to be supported upon the door 2 and to this end I provide the door with a rod receiving 55 socket 9 or 9', referring to the two types of the same shown in Figures 2 and 3, respectively. Preferably I form the door 2 with a suitable socket in its upper edge adapted to receive the rod supporting bushing 9 or 9'. 60 The inclosure is provided with a valance shown and described by me in previous patent applications, and particularly patented to me in U. S. Patent, No. 1,244,692, and this valance consists of a portion 15 disposed 65 above the door heading, separable from the

portion of the inclosure adjacently below, as the inclosure is carried in and out with the door, and a portion 15' disposed laterally of the door heading and integrally secured to the inclosure portion immediately below, all 70 as plainly shown in Figures 1 and 3. The valance portion 15 serves as a bumper for the door section of the inclosure when the same is closed. The inclosure is secured to the canopy frame by means of button elements 12 secured to the lateral portion of the valance and a button element 13 secured to the valance portion 15, as plainly shown in Figures 1 and 3. The portion of the inclosure laterally of the door heading is also 80 secured to the automobile body 1 at the rear lower edge of the inclosure by means of the button elements 11.

In Figures 1 to 8, I have shown three forms of the collapsible type of my improved inclosure and the differences reside in the form of the supporting rod and in the relative arrangement and co-operation of the same with the door 2, the fabric 4 and the longitudinal strengthening member 7. First 85 describing the type shown in Figure 1 which is an inexpensive and simple form, it will be noted that the supporting rod 8 is pivotally secured to the rear face of the strengthening member 7, intermediate of the ends of the latter and is mounted in the tubular bushing 9 carried in the socket of the door 2, the rod 8 being disposed interiorly of the fabric 4. Due to the fact that the overhang 90 of the canopy often extends beyond, or lies within, the vertical projection of the outer edge of the body, I have shown the rod 8, Figure 2, bent in the section where the same enters the door socket, to allow for this canopy irregularity. 95

In the type of curtain shown in Figures 3, 4 and 5, a more expensive type and probably of more pleasing appearance, the supporting rod 8' is incorporated in the fabric 4, the latter being formed with a vertical 100 slot 4' for receiving the rod 8'. Furthermore, the rod consists of two sections, the main supporting section 8' and an upper tip section 8⁴ which is secured to the fabric and preferably is pivotally secured to the longitudinal strengthening member 7, the tip section 8⁴ being formed with a tubular recess for receiving the upper cylindrical rod section 8'. In such a form of supporting rod it is necessary, of course, to obviate the turning of the rod section 8' in the bushing 9' and to this end the cylindrical rod section 8' is formed with a lower end 8⁵ having plane milled side faces which closely register with similar surfaces formed in the 110 bushing 9', this end 8⁵ of the supporting rod and the bushing 9' being co-operatively formed in a manner best suited to this purpose, as shown, described and claimed in my 115 pending application for U. S. Letters Pat- 125

ent upon mounting for automobile side inclosures, Serial No. 554,462. Oftentimes, the supporting rod is mounted in the door 2 so that it cannot extend in a vertical plane 5 to its point of attachment with the fabric 4 or with the longitudinal strengthening member 7, because the rod would then lie too far from the closing edge 4² of the inclosure. Therefore I form an offset in the rod 10 to meet this condition, or some other equally good provision is made, and for the purpose of illustrating this expedient, I have shown the supporting rod of the type in Figure 3 provided with an offset 8².

15 The type of inclosure shown in Figures 6, 7 and 8 is also one in which the supporting rod 8² is incorporated within the fabric 4 but no part of the same is permanently secured either to the fabric 4 or the longitudinal strengthening member 7 nor pivotally secured thereto. This form of rod is formed with an upper open-ended recess 8³ adapted to receive the longitudinal strengthening member 7, as plainly shown in Figure 8, the 20 fabric stitching below strengthening member 7, and intermediate of the ends of the latter, being broken or omitted to allow the entrance of the upper end of the rod 8². The inclosure thus can be rocked upon the 25 upper end of the rod 8² for the purpose of holding its upper edge in its proper horizontal relation to the door. In the forms of inclosure of Figures 3 and 6, of course, the supporting rods 8' and 8², when the inclosures 30 are removed from the door 2, are completely separated from the other inclosure portions and rolled up with the fabric 4 or otherwise suitably stored, when the inclosure as a whole is rolled or folded for 35 storage.

40 In the forms of inclosure shown in Figures 9 to 12, I have embodied my improvements in a rigid frame type. In Figures 9 and 10, I have shown the same form of supporting rod that is illustrated in Figures 3, 4 and 5. In Figures 11 and 12, I have shown the same form of supporting rod that 45 is illustrated in Figures 6, 7 and 8. Instead

of providing a lower stiffening element, such as the sheet metal plate 10 of Figure 1 or the wire netting 10' of Figure 3, I have incorporated flat rod strengthening elements both with the vertical closing edge 4² of the curtain and with the bottom edge 4³ thereof, these strengthening element sections being 50 indicated by the ordinals 7' and 7² and being in fact one continuous member with the upper longitudinal strengthening member 7, thus forming a rigid three-sided frame. In 55 an inclosure thus stiffened by a rigid frame, I have not provided other stiffening means such as the sheet metal plate 10 of Figure 1 or the wire netting 10' of Figure 3.

What I claim is:

1. In an automobile inclosure adapted to 60 be mounted upon the automobile door, the combination of suitable curtain fabric; fabric strengthening means; a supporting member connected to the strengthening means so as to permit a rocking movement 65 of the latter in a vertical plane; and fabric-tensioning means consisting of cooperating elements respectively secured to the fabric and to the automobile door or other support, whereby the upper edge of the inclosure may 70 be held in its proper horizontal relation to 75 the door.

2. In an automobile inclosure adapted to 80 be mounted upon the automobile door, the combination of suitable curtain fabric; fabric strengthening means disposed adjacent the upper edge of the fabric; a supporting member pivotally connected to said strengthening means intermediate of the 85 ends of the latter so as to permit a rocking movement of said strengthening means upon said support; and fabric-tensioning means consisting of cooperating button elements respectively secured to the fabric and the 90 automobile door or other support, whereby the upper edge of the inclosure may be held in its proper horizontal relation to the door.

Signed by me this 23rd day of December, 1921.

GEORGE E. BISHOP.
